UNITED STATES PATENT OFFICE.

ROGER W. DISBRO, OF CLEVELAND HEIGHTS, OHIO, ASSIGNOR TO THE W. S. TYLER COMPANY, OF CLEVELAND, OHIO, A CORPORATION OF OHIO.

ELEVATOR-CAR CONSTRUCTION.

Application filed May 23, 1919, Serial No. 299,177.

To all whom it may concern:

Be it known that I, ROGER W. DISBRO, a citizen of the United States, and a resident of Cleveland Heights, county of Cuyahoga, and State of Ohio, have invented a new and useful Improvement in Elevator-Car Constructions, of which the following is a specification, the principle of the invention being herein explained and the best mode in which

10 I have contemplated applying that principle, so as to distinguish it from other inventions.

The present invention, relating, as indicated, to elevator car construction, is particularly concerned with an improved construction for the walls or sides of elevator cars. In metal elevator cars it is customary to divide each side into two or more panels, each panel consisting of a flat sheet of metal attached at either side to an angular piece, which is fitted around a square piece. The panel proper or angular strip and the post are then fastened together to make up the side of the car, which necessitates a suitable 25 amount of assembly work, and is also open to the objection that the resulting construction is not often light-tight at the different joints.

The present improvements provide a much simpler and more easily assembled elevator side than is possible by the old method, in which the separate sections, which together make up the complete side of the car, are simple and inexpensive in their manufacture 35 and can be readily assembled to produce an attractive and wholly light-tight construction. The present improvements are a modification of the construction described and claimed in my co-pending application filed 40 March 13, 1919, Serial No. 282,350, now issued as patent No. 1,307,187. To the accomplishment of the foregoing and related ends, said invention, then, consists of the means hereinafter fully described and particularly 45 pointed out in the claims.

The annexed drawing and the following description set forth in detail certain mechanism embodying the invention, such disclosure means constituting, however, but one 50 of various mechanical forms in which the principle of the invention may be used.

In said annexed drawing—

Fig. 1 is a horizontal transverse section through an elevator car constructed in accordance with my invention; and Fig. 2 is

an inside partial side elevation of one of the sides of such a car showing its finished appearance.

In Fig. 1 there is shown in outline an elevator car having sides 1, 2, 3 and 4, of which the side 4 is left with an opening 5 for the mounting of a door or gate. The side of the car constructed to receive the door includes three spaced hollow posts 6, each of which is desirably of square cross-section, and in any event should have two or more angularly related sides. Arranged between two of the posts 6 is a flat wall panel 7 of sheet metal, which is provided with an off-set portion 8, to the outer marginal edge of which are integrally connected two angularly related flanges 9 and 10. These angularly related flanges are constructed to have the same angular relation as the nearest two adjacent angularly related sides of the hollow posts 6, so that the panel 7 can be fitted between adjacent posts 6 with the flanges 9 and 10, snugly fitting about and against two adjacent faces of the posts 6, and around one edge of the same, thus securely excluding all exterior light from the inside of the car.

The complete sides 1, 2 and 3 of the car are similarly formed, except that here two or more panels are used, and no opening is left for the mounting of any door or gate. At the corners of the flanges on the panels 7 are connected to the hollow posts in the same way as in the center of the side, with the single exception that the flanges then engage about opposite corners of the posts, instead of about adjacent corners as in the center of the side. It is of course unimportant as to whether the panels 7 are formed with off-set portions 8, or without them, the chief advantage of the off-set being to somewhat stiffen the panel sections, and furthermore to provide a somewhat more attractive appearance for the corners and centers of the sides of the elevator car.

The engaging surfaces of the posts and panels, that is, the two adjacent sides of the post against which the angularly related flanges on the panels lie, may be securely fastened together, either by riveting, bolting, or spot or continuous welding to provide a perfectly light-tight joint along the entire length of the posts. The chief advantages of this improved type of elevator car construction are the convenience and

simplicity of manufacture of the several parts, and the ease with which they may be fitted together and secured, and the construction affords an extremely attractive and relatively less expensive car than it is possible to make with the methods now generally in use.

Other modes of applying the principle of my invention may be employed instead of 10 the one explained, change being made as regards the mechanism herein disclosed, provided the means stated by any of the following claims or the equivalent of such 15 stated means be employed.

I therefore particularly point out and distinctly claim as my invention:—

1. In elevator construction, the combination of a wall section, comprising a hollow closed angular post, a flat panel having 20 angular flanges integral therewith and fitting snugly about and against said angular post.

2. In elevator construction, the combination of a wall section comprising a hollow

closed square post, and flat panels, each having right-angled flanges integral therewith and fitting snugly and flatly against two adjacent right-handed sides of said post.

3. In elevator construction, the combination of a series of aligned closed square hollow posts, and a series of flat panels disposed between said posts and the plane thereof, and said panels having angularly related marginal flanges, such flanges being arranged to engage against the sides and 35 around the one adjacent edge of said hollow posts.

4. In elevator construction, the combination of a series of aligned closed square hollow posts, and a series of flat panels disposed between said posts and in the plane thereof, and said panels having angularly related marginal flanges, such flanges being arranged to engage against the sides and 40 around the outer adjacent edge of said hollow posts.

Signed by me this 16 day of May, 1919.
ROGER W. DISBRO.
